UNITED STATES PATENT OFFICE.

HENRY PHILLIPS AND WILLIAM HUNT, OF OTTUMWA, IOWA.

CAR-LOADER.

SPECIFICATION forming part of Letters Patent No. 570,880, dated November 3, 1896.

Application filed July 27, 1896. Serial No. 600,697. (No model.)

To all whom it may concern:

Be it known that we, HENRY PHILLIPS and WILLIAM HUNT, citizens of the United States, residing at Ottumwa, in the county of Wapello and State of Iowa, have invented certain new and useful Improvements in Car-Loaders; and we do hereby declare the following to be a full, clear, and exact description of the invention, such as will enable others skilled in the art to which it appertains to make and use the same.

Our invention relates to certain new and useful improvements in box or stock car loaders.

It has for its object to provide mechanism which can be conveniently and economically used for expeditiously loading cars either in mines or upon the surface; and with these ends in view our invention consists in the details of construction and arrangement hereinafter fully described.

In the loading of cars with coal it is extremely desirable that the coal should be deposited at each end of the car first and the center subsequently loaded, as in this manner of loading a greater amount can be placed in the cars.

Our improved construction is such that the conveyer which handles and delivers the load can at the will of the operator be moved toward either side or extended forward and retracted while it is in action in delivering the coal.

In the actual use of our improved loading apparatus the load is first delivered at either one of the extreme ends of the car to be loaded, as may be desired, and as the loading progresses the conveyer is moved backward until the loading of that end is finished, at which time the conveyer is in the proper position to commence the loading at the opposite end, which is accomplished by simply reversing the power. It will also be observed after a full understanding of our invention that the coal is delivered gradually and smoothly and without the breaking effect produced by the ordinary loaders which involve the use of a vibrating beam and rotary or oscillating motion.

In order that those skilled in the art to which our invention appertains may fully understand the same, we will proceed to describe its construction and operation, referring by

letters to the accompanying drawings, in which—

Figure 1 is a plan view of a loader embracing our improvements. Fig. 2 is an end view of the same, looking in the direction of the arrow at Fig. 1. Fig. 3 is a side elevation, and Fig. 4 a detail section taken at the line xx of Fig. 3.

Similar letters of reference denote like parts in the several figures.

A represents a suitable frame built on the side of the track opposite to the ordinary coal-chute, and B is an engine or other suitable motor and geared with a main driving-gear C. The top rails D of the frame or support A are provided with antifriction-wheels E, journaled in suitable boxes, and a hopper-frame F rests upon the antifriction-wheels E, as most clearly shown in Fig. 3. At the rear end of the frame A supporting or confining loops G embrace the hopper-frame F in such manner that the latter is free to reciprocate under or within the said loops. The front or free end of the hopper-frame is suitably strengthened by cross-beams H, and mounted pivotally on said frame at its forward end is a crown-pedestal I, having at its base a sur-rounding gear-rack J, meshing with a worm-gear K on the end of a rotatory shaft L, journaled in suitable boxes on the cross-beams H, (see Fig. 1,) which is provided at its rear end with a bevel-gear M, meshing with a similar gear N on a vertical operating-rod O, provided with an operating-wheel P. From this construction it will be seen that with power applied to the wheel P the pedestal I may be rotated in either direction upon its axis.

Secured to the top of the pedestal I are parallel rails Q Q, constituting a top frame, and mounted in these rails near each end thereof are antifriction-wheels R R, (see Fig. 2,) which rotate between the outwardly-projecting flanges of two parallel I-beams S, mounted upon and secured to cross-beams or brace-roads T, in turn secured to the top parallel rails Q Q, the construction and arrangement obviously being such that the I-beam frame S S is free to be reciprocated upon the antifriction-wheels R, so that said frame may be projected and withdrawn in the manner to be presently explained.

U is a coal hopper or receptacle, composed

preferably of boiler sheet-iron and having a bottom V and flaring or oblique side walls W, the upper edges of which are bent, as shown at X, Figs. 3 and 4, to constitute channels for the reception of antifriction and guiding rolls Y, the axles of which are secured by rivets or otherwise to a sliding vertical partition or scraper Z, having wings Z'. The side walls W of the coal-hopper are connected by hinges A' to the bottom V, and the wings Z' of the scraper Z are pivoted at the bottom ends thereto, as shown at B', Fig. 3, and guided at their upper ends through the medium of curved grooves C' and studs D', which construction and arrangement will permit in an obvious manner of the sides W of the hopper (when empty) being folded inwardly to contract its size.

The under side of the hopper is provided with guiding-wheels E' at suitable distances apart, which are adapted to travel between the flanges of the I-beams S on the opposite side of the web to that upon which the anti-friction-wheels R R are located, so that while the I-beams S are free to reciprocate, as stated, upon the wheels R R the hopper U is independently capable of reciprocation upon the said I-beams. One of the I-beams S is formed with a series of stop-holes E', adapted to receive the end of a stop-pin a, operated by a bell-crank foot-lever b, (see particularly Fig. 3,) so that the I-beam frame may be locked at any desired position and freely released when desired.

The scraper or partition Z has secured to its bottom edge a bar F', adapted to reciprocate within a longitudinal slot G' in the bottom V of the hopper, (see Figs. 1 and 2,) which, together with the guide-wheels Y, maintains the scraper in its vertical position.

The main driving-gear C is mounted upon a shaft c, journaled in the main frame A, as most clearly shown at Fig. 1, and upon which shaft is arranged a double clutch operated by a clutch-lever mechanism d in such manner that power may be applied alternately or in opposite directions to the operating-chain H' through the medium of the two feathered driving-pulleys. The operating-chain H', as seen more particularly at Fig. 1, travels around a horizontal pulley K', thence over guiding-pulleys L', thence under the clutch-pulleys I', thence over guiding-pulleys M', thence under pulleys N' and over the transversely-arranged pulleys O', thence around the idlers P' at each end of the I-beam frame, one end of the chain being attached to the forward end of the sliding bar F' and the other end of the said chain to the rear end of said sliding bar, so that as the chain is caused to travel in one or the other direction the scraper Z will be correspondingly moved and will push the coal from one or the other end of the hopper.

Arranged on the frame F is a grip composed of three rollers, (shown in dotted lines at Fig. 3,) the upper one being mounted in the

lower end of a brake stem and wheel Q'. When the upper roller of these three is forced down by the brake stem and wheel, the driving-chain is gripped in such manner that its movement in either one or the other direction will cause the hopper U, as well as the I-beam frame S, to be projected and withdrawn.

The I-beam frame S is provided at the front and rear ends with any suitable stops R' to limit the longitudinal movement of said frame, and the hopper U is also provided with similar stops to limit its longitudinal movement upon the I-beam frame S.

It will of course be understood that the engine B or any other equivalent motor is provided with any desirable means for readily and quickly controlling its action when desired.

The object of constructing the hopper U with hinged sides and the scraper Z with contractible wings C' is in order that the hopper may be laterally contracted when necessary to enter the side door of a freight-car.

As before stated, the loading device is arranged alongside the track and on the opposite side thereof to that occupied by the ordinary coal-chute, and the coal is delivered into the hopper. The I-beam frame and hopper are in parallelism with the main frame F' and support A. The engine or other motor is then started, and the action of the drive-chain H' first causes the main frame F to travel outward toward the car to be loaded and to such an extent as to bring the pedestal I within the car. The worm-gear K is then rotated, and through the medium of its action on the gear J the pedestal and hopper are rotated, so that the former is in parallelism. The I-beam frame S and hopper U are each or both then projected forward to any desired extent or locality and automatically locked in such position. The grip on the driving-chain then being released the clutch mechanism d is then operated so that the chain will cause the scraper Z to force the coal out of the hopper at its forward end and deposit it in the extreme end of the car to be loaded, and as the end of the car is loaded the hopper and frame are correspondingly drawn back so that the coal will fall in the proper locality to successively load the space in the car, and while this is being done the rear end of the hopper is approaching the opposite end of the car and is in position to load that end by causing the scraper to travel in an opposite direction to that which caused it to fill the first end, so that the car to be loaded is filled from the ends toward the center, thus securing more uniform and complete loading than can be accomplished by the ordinary loading devices.

While we have for convenience described the apparatus as located near an ordinary railroad-track, it will be understood that it can be successfully and advantageously used in coal-mines, at coal-docks, or wherever box-cars or similar vehicles are used; and it will

also be understood that the use of our improved loader is not necessarily confined to the loading of coal, but that it may be used wherever it is applicable.

5. We do not wish to be confined to the precise details shown and described, as they may be varied in many particulars without departing from the broad principle of invention, which involves the idea of changing the angle 10 or location of the hopper while the contents of the same are being delivered from the center thereof toward either end, and controlling all the movements of the several parts through the medium of a suitable chain, belt, 15 or rope, and without changing the tension of said chain, belt, or rope.

We have shown the I-beam frame upon which the hopper travels as preferably inclined, so that the hopper is slightly elevated 20 as it approaches each end, but we do not wish to be limited to this precise detail of construction.

Having described the construction and operation of our improved car-loader, what we 25 claim as new, and desire to secure by Letters Patent, is—

1. In a car-loader, a hopper or conveyer provided with a reciprocatory slide or scraper, the conveyer mounted on a track or frame 30 longitudinally movable upon a revolute pedestal or support secured to one end of a reciprocatory main frame traveling upon a suitable support, in combination with a suitable operating belt chain or rope arranged as described, and a driving-engine or other motor, substantially as hereinbefore set forth.

2. The hopper U longitudinally movable upon the reciprocatory I-beam frame S, and provided with a sliding scraper Z adapted to 40 be moved in either direction, whereby the contents of the hopper may be delivered from either end thereof at will, as hereinbefore described.

3. The I-beam frame S adapted to support 45 the hopper U as described, mounted on anti-friction-rollers on the frame Q, and adapted to be turned at different angles through the medium of worm H and gear J, substantially as hereinbefore set forth.

4. In combination with the hopper U, I-beam frame S, frame Q, revolute pedestal I, frame F, and support A, the drive-chain H' traversing the pulleys as described and secured to the sliding bar F' of the scraper Z, in combination with a clutch mechanism d, 55 and a suitable engine or motor B, substantially as and for the purposes hereinbefore set forth.

5. The hopper U composed of the bottom V, hinged sides W, with roller channels or 60 boxes X, in combination with a sliding scraper Z having pivoted contractile wings Z' and antifriction-rollers Y, substantially as and for the purpose set forth.

6. The scraper Z provided with the anti-friction-rollers Y traveling in the channels X of the hopper, and secured at its bottom edge to the reciprocating bar F' sliding in the slot G' in the bottom V of the hopper, whereby the scraper is held in vertical operative position, substantially as hereinbefore described.

7. In combination with the frame Q mounted on the pedestal I and the reciprocating I-beam frame S provided with locking-holes E', 75 the locking device a, b, whereby the frames Q and S may be locked in any given relation or released, as hereinbefore explained.

8. The I-beam frame S traveling on rollers on the frame Q, and located between the exterior flanges of the I-beams, and the hopper U mounted upon antifriction-rollers located and traveling between the interior flanges of the I-beams, thus securing telescopic relation between the parts as shown and described. 80

9. In combination with the frame Q and reciprocating I-beam frame S, stops R' located at each end of the frame S, whereby the movement of said frame in either direction is limited, as hereinbefore described.

In testimony whereof we affix our signatures in presence of two witnesses.

HENRY PHILLIPS.
WILLIAM HUNT.
